(57) **CLAIM**

The ornamental design for television set, substantially as shown and described herein.

DESCRIPTION

FIG. 1 is a front, top, right-side perspective view of a television set showing our new design;

FIG. 2 is a front elevation view thereof;

FIG. 3 is a rear elevation view thereof;

FIG. 4 is a top plain view thereof;

FIG. 5 is a bottom plain view thereof;

FIG. 6 is a left-side elevation view thereof; and,

FIG. 7 is a right-side elevation view thereof.

The broken lines in the drawings are for illustrative purposes only and form no part of the claimed design.
